UNITED STATES PATENT OFFICE.

WILLIAM A. KÖNEMAN, OF CHICAGO, ILLINOIS.

HEATING ATTACHMENT FOR GAS-BURNERS.

SPECIFICATION forming part of Letters Patent No. 732,085, dated June 30, 1903.

Application filed August 11, 1902. Serial No. 119,318. (No model.)

To all whom it may concern:

Be it known that I, WILLIAM A. KÖNEMAN, a citizen of the United States, residing at Chicago, in the county of Cook and State of Illinois, have invented a new and useful Improvement in Heating Attachments for Gas-Burners, of which the following is a specification.

My invention relates to an improvement in portable gas-burning heating devices, for use more especially as room-heating attachments for illuminating-gas burners.

My object is to provide certain improvements in the construction of such a device, primarily to increase its efficiency and desirability as a heater, and also to adapt it for use in a variety of ways, if desired.

In the drawings, Figure 1 is a view of a gas-fixture, showing three of my improved heaters attached thereto for use in different ways; Fig. 2, an enlarged top plan view showing only half the device; Fig. 3, a similar bottom plan view; Fig. 4, an enlarged section taken on line 4 in Fig. 1, where the device is applied directly to the gas-fixture; Fig. 5, a perspective view of a removable vessel-supporting stand adapted for use with the device; Fig. 6, a broken and enlarged section taken on line 6 in Fig. 1, showing the vessel-supporting stand in place; and Fig. 7, a section on line 7 of Fig. 1, where the device is shown suspended from the gas-fixture.

A is the device, having as its main constituent parts a top plate B, a burner-plate C, a partition D, a flaring tube or cylinder E, a central tube F, an air-baffle plate G, a gas-baffle plate H, a strainer I, and a plug F', all constructed, preferably, as shown. The plate portions described may all be of thin sheet metal. In the top of the tube F is an internal screw-thread a, in which fits a removable screw-plug b. The top plate B is bent to present an annular groove c. The plates B, C, and D are fastened together at their outer edges, and this fastening may be effected by flanging one over the other, as shown, by brazing the plates together, or in any other desirable way. At the centers the plates or disks B D are fastened by brazing or otherwise to the tube F, while the cup-shaped disk C is fastened at its center around the tube or cylinder E. The partition-plate D is preferably provided with annular corruga-

tions, as shown. The part C is provided with an annular series of narrow elongated slits or burner-openings d, preferably extending 55 more or less spirally, as shown. The cylinder or tube E is fastened at its lower end around the tube F and partly supports and is partly supported by the plate C. The baffle-plate G is a curved disk fastened around 60 the tube F, and the disk H is flat and also fastened around the tube F. The strainer I fits around the edges of the baffles G H and contacts at its upper and lower ends, respectively, with the partition D and flaring upper end portion of the tube or cylinder E. The plug F' forms a gas-tight diaphragm in the tube F, at the baffle H. In the tube F above the plug are series of perforations e, and below the said plug are series of perforations f. In the lower end of the tube or cylinder E is a series of air-inlet openings g.

The device may be connected with a gas-supply either at the upper or the lower end of the tube F, both said ends presenting gas-supply attaching-openings. In Fig. 7 the device is shown suspended with relation to its support, which support may be an illuminating-gas burner of any kind, a chandelier, as shown in Fig. 1, or any gas-supply connection. When the gas is turned on, it enters the tube F at the top of the latter, its course being indicated by the full-line arrows. Air to mix with the gas enters through openings g and also the lower end of the tube, its course 85 being indicated by dotted arrows. The space between the flaring end portion of the air-tube E and the partition D forms an initial air and gas mixing chamber h, terminating in a comparatively narrow annular outlet h'. 90 The burner-plate C surrounds a larger annular mixing-chamber i, having the burner-outlets d. The gas entering the tube F escapes through the perforations e above the baffle-plate H and through the screen I to the initial 95 mixing-chamber h, into which air is drawn through the openings g and f. Initial mixing takes place in the chamber h, and the mixed gas and air passes into the chamber i and escapes under comparatively little pressure at the burner slits or openings d, where it is ignited. The gas mixture burns over a comparatively large area of the surface of the burner-plate C, producing a blue flame of

high intensity, which heats the plate to a high temperature, so that the radiation of heat therefrom will raise the temperature of the surrounding atmosphere very rapidly.

5 By reason of the fact that the flame heats a metallic surface from which the heat is radiated in the downward direction the best results are obtained in heating a room by having the device more or less near the floor of 10 the room. Thus a desirable way of employing the device is to suspend it from a drop-light tube L, as shown in Figs. 1 and 7. The tube L is provided toward its lower end with a valve l, the connection between the tube 15 and valve being through a wooden or other non-heat-conducting sleeve-piece l', suitably fastened between the tube L and valve or fitting l to prevent the rubber of the tube from being injuriously affected by heat from 20 the heating device. The lower end of the fitting l screws into the threaded attaching-opening a, and the tube L thus holds the device in suspended relation to the chandelier or other support. This construction permits the heating 25 device to hang suspended more or less near the floor of a room, while receiving its gas from above.

The device, as shown, is also adapted to fit at the lower end of its tube F over the illuminating-gas burner on a chandelier or gas- 30 fixture of any kind. When the device is to be used solely in this way for heating a room, the plug b should be in place, as shown in Fig. 4. When the gas is turned on, it enters 35 the lower end of the tube F, its course being indicated by the full-line arrows. Air to mix with the gas enters only through the openings g, as indicated by the dotted arrows. The gas passes through the openings f above 40 the baffle-plate G and the air enters beneath the baffle-plate G, both passing to the initial mixing-chamber h, thence to the mixing-chamber i, and out through the burner-openings d.

If desired, the device may also be employed for heating a small vessel of water. 45 When it is to be used for this purpose, the plug b is removed and a removable burner-cap k (shown in Fig. 6) is placed upon the device to present a small orifice for the escape of a portion of the gas mixture. K is a removable stand having legs fitting into the groove c 50 at the top of the device and presenting a support for a cup or other vessel in which water is to be heated.

55 If desired, the space or chamber m between the plates B D may be filled with asbestos fiber, mineral wool, or other insulating material to maintain the plate D comparatively cool, so that it may be handled by the ringed plug b without danger of burning the fingers.

Constructed as described my improved heating device is not only efficient as a heater, but is ornamental and economical in the use of gas.

65 While I prefer to construct the device throughout as shown and described, it may be variously modified in the matter of details

of construction without departing from the spirit of my invention as defined by the claims.

What I claim as new, and desire to secure 70 by Letters Patent, is—

1. In a gas-burning heater, a casing having burner-openings in its under side, a gas-supply tube extending into the casing and having a gas-discharge opening toward the center of the casing, a baffle-plate in the casing about said tube below the said discharge-opening, an air-inlet opening in the casing beneath said baffle-plate, and a mixing-chamber 75 in the casing about said baffle-plate communicating with said burner-openings. 80

2. In a gas-burning heater, a casing having burner-openings in its under side, a gas-supply tube extending into the casing and having a discharge-opening toward the center of 85 the casing, a baffle-plate in the casing about said tube below the said discharge-opening, an air-inlet opening in the casing beneath the said baffle-plate, a screen about said baffle-plate, and a mixing-chamber in the casing 90 about said screen communicating with said burner-openings.

3. In a gas-burning heater, a casing having a top plate, a bottom plate provided with an annular series of burner-openings, an air-supply tube extending through said bottom plate and terminating beneath said top plate to form an annular discharge-opening, a mixing-chamber about said discharge-opening communicating with said burner-openings, a 95 gas-supply tube extending into the casing and having a gas-discharge opening toward the center of the casing, and an annular baffle-plate in said air-supply tube about said gas-supply tube beneath said gas-discharge 100 openings therein.

4. In a gas-burning heater, a casing having a top plate, a bottom plate provided with an annular series of burner-openings, an upwardly-flaring air-supply tube extending 110 through said bottom plate and terminating beneath said top plate to form an annular initial mixing-chamber and an annular contracted discharge-opening, a second mixing-chamber about said discharge-opening 115 communicating with said burner-openings, a gas-supply tube extending into the casing and having a gas-discharge opening toward the center of the casing, and an annular baffle-plate in said air-supply tube about said gas-supply tube beneath said gas-discharge 120 openings therein.

5. In a gas-burning heater, a casing having a top plate, a bottom plate provided with an annular series of burner-openings, a partition-plate between the top and bottom plates, an air-supply tube extending through said bottom plate and terminating beneath said partition-plate to form an annular discharge-opening, a mixing-chamber about said discharge-opening 125 communicating with said burner-openings, a gas-supply tube extending into the casing and having a gas-discharge opening toward the center of the casing, and an annular baffle-plate in said air-supply tube about said gas-supply tube beneath said gas-discharge 130 openings therein.

neath said partition-plate, and an annular baffle-plate in said air-supply tube about said gas-supply tube beneath said gas-discharge openings therein.

- 5 6. In a gas-burning heater, a casing having a top plate, a bottom plate provided with an annular series of burner-openings, an air-supply tube extending through said bottom plate and terminating beneath said top plate to 10 form an annular discharge-opening communicating with said burner-openings, a gas-supply tube extending through said top and bottom plates, a diaphragm in said gas-supply tube beneath said top plate, the tube 15 having openings above and below said diaphragm, and a baffle-plate in said air-supply tube about said gas-supply tube adjacent to the diaphragm therein.
7. In a gas-burning heater, a casing having 20 a top plate, a bottom plate provided with an annular series of burner-openings, an air-supply tube extending through said bottom plate and terminating beneath said top plate to form an annular discharge-opening, a mixing- 25 chamber about said discharge-opening communicating with said burner-openings, a gas-supply tube extending through said top and bottom plates, a diaphragm in said gas-supply tube beneath said top plate, a baffle-plate

about said gas-supply tube adjacent to said 30 diaphragm, openings in said gas-supply tube above and below said baffle-plate, and a lower baffle-plate about said gas-supply tube beneath the lower openings in said tube.

8. In a gas-burning heater, a casing having 35 a top plate, a bottom plate provided with an annular series of burner-openings, a partition-plate between the top and bottom plates, an air-supply tube extending through said bottom plate and terminating beneath said partition-plate to form an annular discharge-opening, a mixing-chamber about said discharge-opening communicating with said burner-openings, a gas-supply tube extending through said top, partition and bottom plates, 40 a diaphragm in said gas-supply tube beneath said partition-plate, the gas-supply tube having openings directly above and below said diaphragm, a baffle-plate surrounding the gas-supply tube between said openings in 45 said tube and a lower baffle-plate surrounding said gas-supply tube beneath the lower said openings therein.
